Primary Examiner — Mark Goodwin

(57) **CLAIM**

The ornamental design for a wheel loader excavator bucket with bottom mounted ripping teeth, as shown and described.

DESCRIPTION

FIG. 1 is a front perspective view of a wheel loader excavator bucket with bottom mounted ripping teeth showing my new design;

FIG. 2 is a front view thereof;

FIG. 3 is a back view thereof;

FIG. 4 is a left side view thereof;

FIG. 5 is a top view thereof;

FIG. 6 is a bottom view thereof;

FIG. 7 is a right side view thereof; and,

FIG. 8 is another side view perspective thereof.

The broken lines showing of the excavator and the ground is included for the purpose of illustrating environmental structure only and forms no part of the claimed design.

1 Claim, 4 Drawing Sheets
